Filed Nov. 19, 1965, Ser. No. 508,788
4 Claims. (Cl. 248—251)

ABSTRACT OF THE DISCLOSURE

A wall-mounted towel rack consisting of a bar and two mounting brackets at the ends of the bar, one of the brackets having a special right-angled form to fit into a wall corner so that it may be firmly held in place by fasteners driven into a wall stud at the corner.

This invention relates to new and useful improvements in towel rack installations, and in particular the invention concerns itself with towel racks which are mounted by fasteners such as screws on building walls of plaster or plaster-like material.

Such walls are usually supported by horizontally spaced, vertical studs which, of course, are hidden from view, so that when a towel rack is to be mounted on the wall, it is not an easy matter to find the location of the studs in order that the rack mounting screws may be driven thereinto for proper and sturdy support. As a result, the rack mounting screws in most instances take hold in the plaster wall only, and since the wall is relatively thin and of a crumbly character, the screws usually pass through the wall thickness and are easily pulled out, especially under the weight and strain of a towel being placed on or removed from the rack.

It is, therefore, the principal object of the invention to provide an improved towel rack installation which assures that at least one end of the rack is firmly supported by studding, so that the rack is thus able to properly sustain itself in position even if its relatively opposite end is held by screws which engage the wall only.

This object is achieved by the provision of a special towel rack bracket which is particularly adapted for installation in a corner where two right-angularly disposed walls come together and where studding is invariably provided, so that assurance is had that the mounting screws of the special bracket penetrate into the studding and firmly hold the bracket in place.

As such, the special bracket of the invention is simple in construction, economical to manufacture, easy to install, and capable of use in substitution for either one of the two customary brackets commonly provided in a conventional towel rack.

With the foregoing more important object and features in view and such other objects and features as may become apparent as this specification proceeds, the invention will be understood from the following description taken in conjunction with the accompanying drawings, wherein like characters of reference are used to designate like parts, and wherein:

FIGURE 1 is a fragmentary horizontal sectional view of a wall corner, showing in plan the installed towel rack;

FIGURE 2 is an enlarged isometric view of the special corner bracket;

FIGURE 3 is an elevational view of the bracket; and

FIGURE 4 is a plan view thereof, partly in section.

Referring now to the accompanying drawings in details, two right-angularly disposed building walls 10, 11 of plaster or plaster-like material are shown in FIG. 1 as meeting at a corner 12. The walls are supported by horizontally spaced, vertical studs 13, 13, 14, and as a matter of proper building construction, at least one of

2

such studs is always disposed at the corner 12, as for example the stud 14.

The towel rack fixture designated generally by the numeral 15 includes a towel supporting bar 16, the ends of which are carried by a pair of wall mounted brackets, one of which appears at 17. The bracket 17 is a conventional bracket disposed at one end of the bar 16, but in substitution for another like bracket at the other end of the bar, the invention provides a special corner bracket 18. The special corner bracket 18 may be made of metal, plastic, ceramic or any other suitable material, and is particularly intended for installation in the corner 12 against the walls 10 and 11, so that it may be firmly secured as hereinafter described, to one of the corner studs, for example the stud 14. As such, the bracket 18 includes a right-angularly shaped mounting portion 19 which fits against the walls 10, 11 in the corner 12, the portion 19 preferably being bevelled at the corner thereof as indicated at 20 so as to afford a clearance in instances where the wall corner 12 may be somewhat rounded rather than truly square.

A horizontally extending arm 21 is formed integrally with the mounting portion 19 of the bracket, the arm being substantially L-shaped in plan, so that it is joined to both sides or wings of the right-angularly shaped mounting portion 19, as will be clearly apparent. The free end of the arm 21 is formed with a socket 22 to receive one end of the aforementioned towel supporting bar 16, the other end of which is retained in a similar socket provided in the conventional bracket 17.

One side or wing of the mounting portion 19 of the bracket 18 is provided with countersunk apertures 23 for reception of relatively long wood screws 24, these being long enough to pass through the wall 11 into the stud 14, as will be apparent from FIG. 1. It is to be noted that by positioning the bracket 18 in the corner 12 where one or more of the wall studs is always present, assurance is had that the mounting screws 24 will penetrate into the wall stud to firmly support the bracket 18 in position.

The second, conventional bracket 17 may be installed at a selected distance from the bracket 18 in accordance with the length of the towel bar 16 and without regard to spacing or location of the studs 13. The bracket 17 has the usual mounting portion 17' through which screws 25 may be passed into the wall 10. Even if the screws 25 do not enter into a stud and are held by the wall only, the firm mounting of the bracket 18 at the opposite end of the rack will be sufficient to properly hold the fixture in place since, with firm mounting at one end, the strain on the opposite end of the fixture will be substantially minimized.

It may be noted that the bracket 18 is readily reversible so that it may be installed either in the left-hand or the right-hand corner, as desired.

While in the foregoing there has been described and shown the preferred embodiment of the invention, various modifications may become apparent to those skilled in the art to which the invention relates. Accordingly, it is not desired to limit the invention to this disclosure, and various modifications and equivalents may be resorted to, falling within the spirit and scope of the invention as claimed.

What is claimed as new is:

1. A special corner bracket for supporting one end of a towel bar at a corner of two right-angularly disposed building walls, said bracket being formed integrally from one piece of material and comprising a right-angular mounting member including first and second vertical wings connected together at the corner of the mounting member, said wings having outer faces and inner wall engaging faces, and a substantially L-shaped arm member including a rectangular base joined along two adjacent

of its sides to the outer faces of the respective wings, and an arm extending horizontally from said base at right angles to the first wing and in laterally outwardly spaced relation from the plane of the outer face of the second wing, the outer end portion of said arm being provided with a towel bar receiving socket open in a direction away from the second wing, and the second wing being provided with apertures for reception of fastener elements.

2. The device as defined in claim 1 wherein said arm member has a smaller vertical dimension than said mounting member with upper and lower surfaces of the arm member being spaced respectively downwardly and upwardly from upper and lower edges of said wings, said apertures in the second wing being located above and below the planes of the respective upper and lower surfaces of the arm member.

3. The device as defined in claim 1 wherein said arm member has an outer side edge flush with an outer side

edge of the first wing, said socket being provided in the outer side edge of the arm member.

4. The device as defined in claim 1 wherein the inner faces of said wings are bevelled at the corner of said mounting member.
